UNITED STATES PATENT OFFICE.

HARRY ARTHUR FOOTHORAP, OF HARRISBURG, PENNSYLVANIA, ASSIGNOR TO ELLIOTT-FISHER COMPANY, OF HARRISBURG, PENNSYLVANIA, A CORPORATION OF DELAWARE.

RIBBON-SPOOL FOR TYPEWRITERS.

1,378,672.

Specification of Letters Patent. Patented May 17, 1921.

Original application filed December 14, 1914, Serial No. 877,216. Divided and this application filed August 17, 1918. Serial No. 250,315.

To all whom it may concern:

Be it known that I, HARRY ARTHUR FOOTHORAP, citizen of the United States of America, residing at Harrisburg, in the 5 county of Dauphin and State of Pennsylvania, have invented certain new and useful Improvements in Ribbon-Spools for Type-writers, of which the following is a specification.

10 This invention relates to a novel ribbon spool adapted more particularly for use in connection with machines of that type characterized by a stationary platen and downwardly acting printing mechanism.

15 The mechanism shown in the accompanying drawings is also shown and described in applicant's copending application for Letters Patent of the United States Serial No. 877,216, filed Dec. 14, 1914, of which this is 20 a division. Only so much of the mechanism disclosed in said copending application as is necessary to the understanding of the features of the invention claimed herein is shown and described in the present application.

25 The object of the invention is to produce an efficient and inexpensive ribbon spool, the primary elements of which are accessibly carried by the escapement brackets.

30 To the accomplishment of the above recited object and others which will more fully hereinafter appear, one embodiment of the invention resides in the construction and arrangement of parts illustrated in the accompanying drawings, described in the following specification, and succinctly defined 35 in the appended claims.

In the accompanying drawings:

Figure 1 is a side view of the ribbon spool. 40 Fig. 2 is a sectional view of the ribbon spool, and its mountings.

Fig. 3 is a view of the outer hub section. Fig. 4 is a view of the ribbon cup or barrel. 45 Fig. 5 is a view of the inner hub section.

Fig. 6 is a view of the carrying spindle. Fig. 7 is a view of the ribbon cup or barrel showing the end opposite to that illustrated in Fig. 4.

50 The machine to which my ribbon spool is particularly adapted is what is known as the Elliott-Fisher billing machine which is of that type in which the platen is stationary and above which moves longitudinally a line space frame supporting a carriage which is

movable transversely of the platen to letter space the writing accomplished by a downwardly acting printing mechanism mounted on and movable with said carriage.

55 The typewriter carriage shown in my application as above cited is not illustrated in the present application, and while it is designed to use a pair of the spools such as described one only has been illustrated.

60 The spools are supported from the carriage by brackets, a portion of one of which is shown at 1.

65 Each of the ribbon spools is carried by a spindle 2 extended outwardly and fixed at one end only to the arm 1 and provided with a reduced outer end 3 between which and 70 the body of the spindle is defined an enlargement or collar 4. On the spindle proper rotates a hub section 5 formed with what may be termed the pin flange 6 from which

75 project radially one or more clutch pins 7. The flange 6 is spaced from the bracket 1 sufficiently to permit the interposition of a spool pinion 8 between which and the pin flange is held the inner or rear spool flange 9. The outer end of the hub section 80

5 is formed with an axial recess 10 which accommodates the flange 4 of the spindle and is internally threaded, as shown in Fig. 2, to receive the externally threaded inner 85

end of the outer hub section 11 provided with a knurled head 12 and with an axial bore 13 for the reception of the reduced end of the spindle upon which it rotates. Rotatable on the outer hub section 11 adjacent 90

to the knurled head and held in place thereby is a flange ring 14 to which is secured the outer spool flange 15. The ribbon R is secured to the spool by what is known as a ribbon cup or barrel 16 which is a thin metal shell of cylindrical form having a 95

depressed bottom or outer end 17 formed with an opening to receive the threaded inner end of the outer hub section 11 and retained between the flanges 15 and 9. The shell cup or barrel 16 is also formed with a 100

longitudinal slit 18 through which the ribbon R is passed and retained by a metal tab 19 located within the cup and too large to be drawn through the slit 18. As clearly shown in Fig. 7, the slit 18 opens at the inner end of the cup and permits the ribbon to be slipped into place without the necessity for separate securing devices. The 105

inner edge of the cup or shell 16 is provided with one or more notches 20, which, when the shell is slipped to its place on the inner spool section, engage the pin 7 which thus 5 compel the ribbon, shell and spool to rotate in unison. One of these notches 20 is preferably formed at the end of the slit 18 so that, when the shell is in place, one of the pins positively closes the end of the slit 10 and precludes any sidewise working of the ribbon.

Referring to Fig. 2, let us assume that it is desired to replace the ribbon. By grasping the knurled head 12, the outer spool 15 section may be removed or unscrewed from the inner spool section. The ribbon fastening device or shell 16 with the ribbon wound thereon is then slipped off. Another shell with a new ribbon wound thereon may then 20 be slipped upon the inner spool section and engaged by the pins 7 where it will be held by the flange 15, when the outer spool section is screwed back into place.

What I claim is:—

- 25 1. The combination with a hub section, of a spindle rotatably supporting said section, means retaining the hub section against endwise movement on the spindle, a second hub section also rotatable on the spindle and movable longitudinally thereof to connect with the hub section first named and a ribbon shell rotatable with the hub sections and removable when said hub sections are disconnected.
- 30 2. The combination with a spindle having a shoulder, of a hub section confined on the spindle by the shoulder, a second hub section rotatable on the spindle and connected with the first named hub section for rotation therewith but separable therefrom and from the spindle.

3. The combination with a spindle having a reduced end and a shoulder intermediate of its ends, of a hub section confined on the spindle by the shoulder thereof, a second hub section screwed into the first named hub section and rotatable on the reduced end of the spindle and a ribbon shell rotatable with and carried by the hub sections. 45

4. The combination with a hub section 50 having radial pins, of a shell having notches engaging the pins and a second hub section screwed into the first named hub section and confining the shell in its pin engaging position. 55

5. A resilient ribbon shell or core having a longitudinal open ended slit to accommodate the ribbon and a plurality of notches in one edge for the engagement of its support, one of said notches being formed by 60 the enlargement of the open end of the slit and facilitating the insertion of the ribbon in said slit.

6. A ribbon shell or core having an end formed with an opening of smaller diameter 65 than the diameter of the shell, to facilitate the support of the shell and said shell being also provided with a ribbon retaining slit, and with a notch facilitating the retention of the shell on a ribbon spool. 70

7. The combination with a hub section having radial pins and a spool pinion, of a shell having a ribbon receiving slit and notches engaging the pins, and a movable hub section engaging the hub section first 75 named and confining the shell.

In testimony whereof I affix my signature in the presence of two witnesses.

HARRY ARTHUR FOOTHORAP.
